TABLE LAMP

Clarence R. Swanson, Minneapolis, Minn.

Application May 16, 1955, Serial No. 36,009

Term of patent 3½ years

(Cl. D48—20)

FIG. 1

Fig. 1 is a front elevational view of a table lamp, showing my new design; and

Fig. 2 is a rear perspective view thereof to a smaller scale.

I claim:

The ornamental design for a table lamp, as shown.
